UNITED STATES PATENT OFFICE.

JOHN G. CLEMENS, OF BUFFALO, NEW YORK, ASSIGNOR, BY MESNE ASSIGNMENTS, TO
EDWIN D. CAHILL, OF HAMILTON, ONTARIO, CANADA.

RENEWABLE FUSE PLUG.

Application filed September 11, 1920. Serial No. 409,621.

To all whom it may concern:

Be it known that I, JOHN G. CLEMENS, a citizen of the United States, residing at Buffalo, in the county of Erie and State of New York, have invented certain new and useful Improvements in Renewable Fuse Plugs, of which the following is a specification.

This invention relates to renewable fuse plugs and has as one of its objects to provide a plug so constructed that when the fuse is blown the generated gases will be permitted to expand and become somewhat cool before escaping to the atmosphere thus eliminating the noise which usually results from blowing of a fuse plug, and also preventing the discharge of flames from the plug.

Another object of the invention is to so construct the plug that the arc produced upon blowing of the fuse will not follow along the fusible element of the plug for any considerable portion of its length so there will be no likelihood of the arc burning through the shell of the plug and probably causing damage to the plug socket.

Another object of the invention is to provide for maximum protection being afforded the shell of the plug to prevent the shell being burned through at the time of burning of the fuse.

A further object of the invention is to provide a plug the fusible element of which may be readily renewed whenever required.

In the accompanying drawings:

Figure 1 is a perspective view illustrating the plug embodying the invention, the parts being separated;

Figure 2 is a detail vertical longitudinal sectional view through the plug, all parts thereof being assembled;

Figure 3 is a perspective view of the renewable fusible element.

The plug embodying the invention comprises an outer member indicated in general by the numeral 1 and an inner member indicated in general by the numeral 2. The outer member consists of a shell 3 of brass or any other suitable metal open at one end and closed at its other end as indicated by the numeral 4. From its open end, for any desired portion of its length, the shell 3 is crimped to provide threads 5 so as to adapt this end of the shell to receive the member 2 which for this purpose is likewise pro-

vided with threads 6. The outer member 1 likewise consists of a cap 7 which is of porcelain or any other suitable insulating material and which is fitted onto its closed end. The cap 7 more or less snugly encompasses the closed end portion of the shell 3, and the open end portion of the shell projects beyond the open end of the cap a sufficient distance to adapt the plug as a whole to be threaded into its socket. In order to secure the shell and cap together, a metallic disk 8 is disposed within the closed end of the shell and is provided with threaded openings 9 receiving the ends of screws 10 which are passed through openings 11 in the closed end of the cap and the closed end of the shell, the heads of the screws when tightened bearing against the said end of the cap. For a purpose to be presently explained a disk 12 of any suitable insulating material is arranged within the closed end of the shell 3 and covers the face of the disk 8.

The inner member 2 of the plug comprises a body 13 preferably of porcelain which body is provided at its outer end with a polygonal boss 14 whereby the body may be threaded into the shell 3 in assembling the two members of the plug. The body is provided at its opposite or inner end with an axially located neck 15 which is of a diameter considerably less than that of the body, and the said body and its neck 15 are formed with an axially extending bore 16 which constitutes an explosion chamber as will be presently explained, this bore opening through the end of the neck 15 and terminating short of the outer end of the body, the said end of the body being however formed with a small opening or slot 17 communicating with the corresponding end of the chamber 16.

The fusible element of the plug is indicated in general by the numeral 18 and, as most clearly shown in Figure 3 of the drawings, comprises a head 19 which may be of sheet metal crimped or otherwise formed to secure it to the doubled or folded end 20 of a strip of metal 21 which constitutes the fusible element proper. A washer 22 of insulating or any other suitable material is fitted onto the end portion 20 of the fusible element and, when this portion of the element is fitted through the opening or slot 17, lies between the outer end of the body 13 of the inner plug member and the head 110

19 of the fusible element and serves to close or seal the said opening 17 substantially in an airtight manner. The head 19 constitutes of course a contact head, and in order 5 that the current may be conducted by the fusible element to the shell 3, the strip comprising the element is led through the explosion chamber 16 to the outer end thereof and is then bent over the end of the neck 10 15, as indicated by the numeral 23, and has its terminal portion seated between the wall of the shell 3 and the outer surface of the body 13, this terminal portion, which is indicated by the numeral 24, being crimped 15 as indicated by the numeral 25 to fit the threads of the body 13 and shell 3. The crimped portion 25 of the fusible element extends between the body 13 and shell 3 but terminates short of the outer end of the 20 said body so that while this portion of the fusible element serves to somewhat space the wall of the shell at one side from the corresponding side of the body 13, nevertheless the endmost threads of the shell and 25 body or in other words those located beyond the extremity of the portion 25 are somewhat closely in contact so as to somewhat restrict this space. The strip 21 is preferably reduced in width throughout the portion 30 of its length which extends through the chamber 16, as indicated by the numeral 26, so that when the element fuses, the arc will be formed at this point.

From the foregoing description of the invention it will be understood that when the 35 fusible element is fused, the arc will be formed within the explosion chamber 16 and will be restricted to this chamber because of the relatively small size of the chamber, the 40 heated gases generated passing from the chamber into the space within the shell 3 which surrounds the neck 15 and which space constitutes an expansion chamber indicated by the numeral 27. After leaving the chamber 45 16 and expanding within the chamber

27, the gases will leave the latter chamber, passing out in a more or less gradual manner through the space between the wall of the shell 3 and the outer surface of the body 13, which space is provided as before stated, 50 by the presence of the portion 25 of the fusible element. Thus by the time the gases reach the atmosphere they will have expanded and become cool and therefore there is no noise or report created upon blowing 55 of the fuse nor is there any likelihood of flames being discharged from the plug. The disk 12 serves to protect the disk 8 and closed end of the shell 3 from the gases as they are discharged from the open end of 60 the explosive chamber.

Having thus described the invention, what is claimed as new is:

A renewable fuse plug comprising a metallic shell closed at one end and open at 65 its opposite end and provided in its wall with threads, a threaded body of insulating material removably fitted into the open end of the shell and provided with a bore extending longitudinally thereof and constituting 70 an explosion chamber, the bore opening through the inner end of the said body, the body being reduced in diameter throughout its inner portion to provide a neck of considerably less diameter than the interior 75 of the shell, and consequently considerably spaced from the wall thereof, the end of the neck being spaced from the closed end of the said shell whereby an expansion chamber is provided in direct communication with the 80 explosion chamber in the body, and a fusible element having one end extending through the closed outer end of the body and being led through the explosion chamber and over the end of the neck and disposed at its other 85 end between the outer side of the said body and the wall of the shell and in electrical contact with the latter.

In testimony whereof I affix my signature.
JOHN G. CLEMENS. [L.S.]
